(57) **CLAIM**

The ornamental design for a dental curing light sleeve, as shown and described.

DESCRIPTION

FIG. 1 is an isometric view of a dental curing light sleeve, embodying a new design;

FIG. 2 is a top plan view of the dental curing light sleeve of FIG. 1;

FIG. 3 is an isometric view of a dental curing light sleeve, embodying a new design; and,

FIG. 4 is a top plan view of the dental curing light sleeve of FIG. 3.

The broken lines shown in the figures represent portions of the dental curing light sleeve that form no part of the claimed design. The surface shading illustrated in the drawings is provided merely to highlight the contour of the design and is not part of the claimed design.
